DIVIDER BLADE MECHANISM FOR MATERIALS SEPARATING MACHINES

Ralph H. Johnson, Rochester, N. Y., assignor, by
mesne assignments, to The Quaker Oats Company, Chicago, Ill., a corporation of New Jersey

Application May 18, 1946, Serial No. 670,701

12 Claims. (Cl. 209—130)

1

This invention relates to mechanism comprising an adjustable divider blade for attachment to machines for the dry separating and classifying of finely divided materials, such, for example, as the known mechanical or electrostatic separating machines. In the operation of such separating machines, it is important that the divider blade be accurately located in such position in the stream of falling particles as to cleanly effect the desired separation, with the particles of different characteristics falling on opposite sides of the blade. In many cases, particularly where the machine and blade are of substantial length, say, twelve feet long, or when the machine is enclosed in a dust retaining casing, it is often difficult to see and obtain access to such divider bars and to effect and maintain such adjustments, equally and accurately at both ends of the blade.

One object of the invention, therefore, is to provide an improved divider blade mechanism having efficient means for adjusting the position of the blade, accurately and uniformly, at both of its ends, relatively to the stream of materials to be separated, to suit particular operating conditions.

Another object is to provide such a mechanism capable of being readily and conveniently operated from the outside of the machine frame or casing in which it may be enclosed.

A further object is to provide a mechanism having the above advantages in a form of construction adapted to be easily attached to the frame of a separating machine.

A still further object is the provision of a mechanism of the above character in a simple, rugged, and reliable form of construction capable of being economically manufactured and installed.

To these and other ends the invention resides in certain improvements and combinations of parts, all as will be hereinafter more fully described, the novel features being pointed out in the claims at the end of the specification.

In the drawings:

Fig. 1 is a side elevation of portions of an electrostatic separating machine having attached thereto a divider blade mechanism embodying the present invention;

Fig. 2 is a top plan view of the same, partly in section and partly broken away;

Fig. 3 is an enlarged side elevation as seen from the left in Fig. 1, with parts of the machine frame broken away;

Fig. 4 is an enlarged perspective view of a rack bar employed in the mechanism;

2

Fig. 5 is a sectional elevation on the line 5—5 in Fig. 3;

Fig. 6 is a sectional plan view on substantially the line 6—6 in Fig. 5;

Fig. 7 is an enlarged sectional elevation on the line 7—7 in Fig. 6;

Fig. 8 is an enlarged elevation, partly in section, on the line 8—8 in Fig. 6, and

Fig. 9 is an enlarged sectional elevation on the line 9—9 in Fig. 5.

The preferred embodiment of the invention, herein disclosed by way of illustration, is adapted for application to an electrostatic separating machine comprising spaced end frames or standards, indicated generally at 10 and 12 (Figs. 1—3), each built up of hollow metal sections 13, flanged as at 14, and bolted together as at 15, in superposed relation. Journaled at their opposite ends in these frame sections are the shafts 16 carrying the pairs of spaced cylindrical electrodes usually including a larger rotary conveying electrode 17, and a smaller electrode 18 spaced therefrom, the finely divided materials to be separated being discharged from hopper means (not shown) on the rotary conveying electrode 17. Such materials are delivered by the electrode 17 in a free falling stream through an electrostatic field produced between the electrodes, with the result that the particles are repelled or depressed, according to their characteristics, and thus separated into spaced planes for division into different classes by the divider blade 10. One of the separated classes of particles may then be conveyed to the next lower pair of electrodes 20 for further or different treatment, to progressively effect the desired separation, as well understood in the art.

Where such mechanisms are adjustably supported, as heretofore, by means located within the frame or casing of the machine, they have been difficult to reach, often requiring the manipulation of the parts in dangerous proximity to highly charged electrical conductors, requiring discontinuance of the operation of the machine during such adjustments. Moreover, it has been found difficult and tedious, particularly in the case of divider bars of substantial length, to accurately adjust the bar, one end at a time, while maintaining it in parallelism with the plane of the materials to be separated.

I have found that this difficulty may be advantageously overcome by the provision of an improved divider blade mechanism adjustably mounted in a simple way on the outside of the end standards 10 and 12 of the separating machine. For this purpose I preferably provide rack

bars 21 of the character shown in Fig. 4, for bolting to the frame standards, as shown in the several figures of the drawings. Each rack is recessed at the rear of the side lying against the standard, as at 22, to form with the standard wall a guide channel in which is received a gib 23 (Figs. 6 and 8) bolted to the outer side of each of a pair of gear boxes 24 and 25, one adjacent each of said frame standards. By means of such gibs, the gear boxes are retained and guided on the frame for limited vertical adjustment.

Each gear box has each of opposite walls thereof formed with bearings 26 and 27 (Fig. 5) in which are journaled the respective ends of a shaft 28 extending between the boxes. Fixed on each end of the shaft within each box is a pinion 29 meshing with the corresponding rack 21. Fixed on one end of shaft 28 in box 24 is a worm wheel 30 (Figs. 5 and 6) meshing with a worm 31 fixed on a short shaft 32 journaled in bearings in opposite walls of the box and projecting forwardly through the front wall as at 33 and formed for the reception of a crank 34, Fig. 2. It will be apparent that by means of such gearing, rotation of shaft 32 serves to rotate shaft 28 and its pinions meshing with the racks on the frame, so as to simultaneously elevate or lower both gear boxes 24 and 25, equally, for the purpose of raising or lowering the divider blade carried by the boxes, as hereafter described.

Another shaft 35, Figs. 5 and 9, is journaled at its ends in bearings in opposite side walls of the gear boxes 24 and 25, this shaft having its end at the right hand side of the mechanism projecting outside the gear box as at 36 and formed for the reception of a hand crank 37, Fig. 1, for rotating the shaft. Fixed on shaft 35 in each of the gear boxes is a spiral gear 38 meshing with a similar gear 39 fixed on a spindle 40 journaled in bearings in the front and rear walls of each box. Each spindle 40 is extended rearwardly beyond its box and provided with a screw thread as at 41. A pair of spaced heads 42 are each provided with a threaded opening 43 in which the corresponding threaded spindle 41 is received, these heads 42 being connected by and forming the support for the divider blade 19. For this purpose the divider blade is clamped between the flanged edges 44 of a sleeve 45 fixed by bolts 46 on solid end trunnions 47. Trunnions 47 are clamped in split bearings in the upper ends of the heads 42 which are tightened by means of bolts 48, Fig. 3, so as to securely hold the divider blade in adjusted position on the heads.

The heads 42 are also connected by a bar 49, Fig. 3, on which a baffle plate 50 is pivotally mounted by means of a semi-circular flange 51 at its upper end hooked over the bar. Baffle plate 50 rides at its lower end, during adjustments of the divider bar, on a support 52 on the machine frame. The baffle is thus located below the divider blade in position to intercept particles falling on the rear side thereof and to discharge such particles to a chute 53 for suitable disposition.

It will be noted that each of the equalizer shafts 28 and 35 has an intermediate tubular section as at 54 (Fig. 5) adjustably coupled with the opposite ends of each shaft by means of sleeve 55. Each sleeve is adjustably fixed to the intermediate tube and adjacent shaft end by means of set-screws 56. By this means, and by the use of the worm and spiral types of gearing employed, substantially all backlash and lost motion is eliminated so as to insure equal and

precise adjustment of the ends of the divider bar.

It is apparent from the above described construction that the rotation of shaft 33, by means of the hand crank 34, serves to rotate shaft 28 and its pinions 29 meshing with the stationary racks on the frame, thus raising or lowering the gear box housings 24 and 25 so as to raise or lower both ends of the divider blade with equalized precision. Similarly, rotation of shaft 35, by means of crank 37, serves to rotate each of the threaded spindles 40, in one direction or the other, and thus adjust the heads 42 and the divider blade toward or from the conveying electrode 17, with equalized precision, so as to maintain the blade parallel with the plane of separation of the materials. Such vertical and horizontal adjustments are thus separately accomplished, each by a single hand crank conveniently located on the outside of the machine. The mechanism affords a wide range of adjustment of the blade, as indicated by the full and dotted line positions shown in Fig. 3, and the blade is thus quickly, accurately, and conveniently brought to the most advantageous position for any particular operating condition. At the same time, baffle plate 50 is self adjusting to position to receive one of the classes of particles separated by the blade and to discharge it separately from the other class of materials which is conveyed by suitable baffle means 57 to the next lower pair of electrodes.

It will thus be seen that the invention accomplishes its objects and while it has been herein disclosed by reference to the details of preferred embodiments, it is to be understood that such disclosure is intended in an illustrative, rather than in a limiting sense, as it is contemplated that various modifications in the construction and arrangement of the parts will readily occur to those skilled in the art, within the spirit of the invention and the scope of the appended claims.

I claim:

1. An electrostatic machine for separating materials having different electrostatic susceptibilities comprising a frame having an elongated electrode, an elongated divider blade in spaced parallel relation to said electrode, a housing associated with each end of said blade, spindles rotatably mounted in said housings and having threaded connections with the ends of said blade, respectively, for supporting and adjusting the same in one direction relative to said electrode, adjusting means in said housings having connections with said frame for supporting and adjusting said housings in another direction relative to said electrode, equalizing means having actuating connections with said spindles to effect simultaneous equal rotation thereof, equalizing means having actuating connections with said housing adjusting means to effect simultaneous equal actuation thereof, and means for operating said adjusting means for effecting equalized adjustment of the ends of said blade in each of said directions.

2. An electrostatic machine for separating materials having different electrostatic susceptibilities comprising a frame having an elongated electrode, an elongated divider blade in spaced parallel relation to said electrode, a housing associated with each end of said blade, adjusting means in said housings having connections with the ends of said blade, respectively, for supporting and adjusting the same in one direction relative to said electrode, rack and pinion means connecting said frame and hous-

ings for adjusting said housings in another direction relative to said electrode, equalizing means having actuating connections with said blade adjusting means to effect simultaneous equal actuations of the ends of said blades, a shaft connecting the pinions of said rack and pinion means to effect simultaneous equal rotation of said pinions, and means for operating said blade adjusting means and for rotating said shaft for effecting equalizing adjustment of the ends of said blade in each of said directions.

3. An electrostatic machine for separating materials having different electrostatic susceptibilities comprising a frame having an elongated electrode, an elongated divider blade in spaced parallel relation to said electrode, a housing associated with each end of said blade, spindles rotatably mounted in said housings and having threaded connections with the ends of said blade, respectively, for supporting and adjusting the same in one direction relative to said electrode, rack and pinion means connecting said housings with said frame for adjusting said housings in another direction relative to said electrode, a shaft having actuating connections with said spindles for effecting simultaneous equal rotation thereof, a shaft connected with the pinions of said rack and pinion means for effecting simultaneous equal rotation thereof, and means for rotating said shafts for effecting equalized adjustment of the ends of said blade in each of said directions.

4. An electrostatic machine for separating materials having different electrostatic susceptibilities comprising a frame having an elongated electrode, an elongated divider blade in spaced parallel relation to said electrode, a gear box associated with each end of said blade, adjusting means in said boxes having connections with the ends of said blade, respectively, for supporting and adjusting the same in one direction relative to said electrode, gearing in said boxes connected with said frame for supporting and adjusting said boxes in another direction relative to said electrode, a shaft having gearing connections in said boxes with said blade adjusting means for effecting simultaneous equal actuation thereof, a shaft having its ends connected with said gearing for effecting simultaneous equal adjustment of said boxes, and means for rotating said shafts for effecting equalized adjustment of the ends of said blade simultaneously in each of said directions.

5. An electrostatic machine for separating materials having different electrostatic susceptibilities comprising a frame having an elongated electrode, an elongated divider blade in spaced parallel relation to said electrode, a housing associated with each end of said blade, adjusting means in said housings having connections with the ends of said blade, respectively, for supporting and adjusting the same in one direction relative to said electrode, racks on said frame, pinions in said housings meshing with said racks, a shaft having actuating connections with said blade adjusting means for effecting simultaneous equal actuation thereof, a shaft connected with said pinions for effecting simultaneous equal rotation thereof, means for rotating each of said shafts for effecting equalized adjustment of the ends of said blade simultaneously in each of said directions, and guide means on said racks and housings for retaining and guiding said housings on said frame during said adjustment thereof.

6. An electrostatic machine for separating ma-

terials having different electrostatic susceptibilities comprising a frame having an elongated electrode, an elongated divider blade in spaced parallel relation to said electrode, a housing associated with each end of said blade, spindles rotatably mounted in said housings and having threaded connections with the ends of said blade, respectively, for supporting and adjusting the same in one direction relative to said electrode, racks on said frame, pinions in said housings meshing with said racks, respectively, for adjusting said housings in another direction, gibs on said housings engaging said racks to retain and guide said housings on said frame, a shaft provided at its ends with actuating connections with said spindles for effecting simultaneous equal rotation thereof, a shaft connected with said pinions for effecting simultaneous equal rotation thereof, and means for rotating said shafts for effecting equalized adjustment of the ends of said blade simultaneously in each of said directions.

7. An electrostatic machine for separating materials having different electrostatic susceptibilities comprising a frame having an elongated electrode, an elongated divider blade relative to said electrode, a gear box associated with each end of said blade, spindles rotatably mounted in said boxes and having threaded connections with the ends of said blade, respectively, for supporting and adjusting the same in one direction relative to said electrode, racks on said frame, pinions meshing with said racks, respectively, a shaft having gearing connections at its ends with said spindles for effecting simultaneous equal rotation thereof, a shaft connected at its ends with said pinions for effecting simultaneous equal rotation thereof, and means for rotating said shafts for effecting equalized adjustment of the ends of said blade simultaneously in each of said directions.

8. An electrostatic machine for separating materials having different electrostatic susceptibilities comprising a frame having an elongated electrode, an elongated divider blade, in spaced parallel relation to said electrode, a gear box associated with each end of said blade, spindles rotatably mounted in said boxes and having threaded connections with the ends of said blade, respectively, for supporting and adjusting the same in one direction relative to said electrode, racks on said frame, pinions meshing with said racks, respectively, gibs on said boxes and engaging said racks for retaining and guiding said boxes on said frame, a shaft having gearing connections at its ends with said spindles for effecting simultaneous equal rotation thereof, a shaft connected at its ends with said pinions for effecting simultaneous equal rotation thereof, and means for rotating said shafts separately to effect simultaneous equalized adjustment of the ends of said blade in either of said directions.

9. An electrostatic machine for separating materials having different electrostatic susceptibilities comprising a frame having an elongated electrode, an elongated divider blade in spaced parallel relation to said electrode, a housing associated with each end of said blade, adjusting means in said housings having connections with the ends of said blade, respectively, for supporting and adjusting the same in one direction relative to said electrode, adjusting means in said housings having connections with said frame for supporting and adjusting said

7
housings in another direction relative to said electrode, a baffle plate underlying said blade and pivotally connected thereto for conveying materials separated by said blade, actuating and equalizing means connecting each adjusting means of one housing with the corresponding adjusting means of the other housing to effect simultaneous equal actuation thereof, and means for operating said adjusting means for effecting simultaneous equalized adjustment of the ends of said blade in each of said directions.

10. An electrostatic machine for separating materials having different electrostatic susceptibilities comprising a frame having an elongated electrode, an elongated divider blade in spaced parallel relation to said electrode provided at its ends with supporting heads, a gear box associated with each end of said blade, spindles each having one end rotatably mounted in one of said boxes and the other end threadedly connected with one of said heads, for supporting and adjusting the same in one direction relative to said electrode, rack and pinion means connecting said boxes with said frame for adjusting said boxes in another direction relative to said electrode, a rod connecting said heads below said blade, a baffle pivotally supported on said rod below said blade for conveying materials separated by said blade, a shaft having gearing connections at its ends and said spindles to effect simultaneous equal rotation thereof, a shaft connected with the pinions of said rack and pinion means for effecting simultaneous equal rotation thereof, and means for rotating said shafts for effecting simultaneous equalized adjustment of the ends of said blade in each of said directions.

11. An electrostatic machine for separating materials having different electrostatic susceptibilities, comprising a frame having an elongated electrode, an elongated divider blade in spaced parallel relation to said electrode, a housing associated with each end of said blade, adjusting means in said housings having connections with the ends of said blade, respectively, for supporting and adjusting the same in one direction relative to said electrode, adjusting means in said housings having connections with said frame for supporting and adjusting said housings and the first mentioned adjusting

5 means in another direction relative to said electrode, a common actuating element connected with the blade adjusting means of said housings, a common actuating element connected with said housing adjusting means, and means for operating said elements to effect simultaneous equalized adjustment of the ends of said blade in each of said directions.

12. An electrostatic machine for separating materials having different electrostatic susceptibilities, comprising a frame having an elongated electrode, an elongated divider blade in spaced parallel relation to said electrode, a housing associated with each end of said blade, adjusting means in said housings having connections with the ends of said blade, respectively, for supporting and adjusting the same in one direction relative to said electrode, adjusting means in said housings having connections with said frame for supporting and adjusting said housings and the first mentioned adjusting means in another direction relative to said electrode, a shaft having actuating connections with the blade adjusting means of said housings, a shaft having actuating connections with said housing adjusting means, and means for rotating said shafts to effect simultaneous equalized adjustment of the ends of said blade in each of said directions.
